UNITED STATES PATENT OFFICE.

SAMUEL E. OVERTON, OF SOUTH HAVEN, MICHIGAN.

BENCH OR SEAT.

1,288,974.

Specification of Letters Patent. Patented Dec. 24, 1918.

Application filed October 18, 1918. Serial No. 258,692.

To all whom it may concern:

Be it known that I, SAMUEL E. OVERTON, a citizen of the United States, residing at South Haven, in the county of Van Buren 5 and State of Michigan, have invented certain new and useful Improvements in Benches or Seats, of which the following is a specification.

This invention relates to improvements 10 in benches or seats.

My improvements are particularly designed by me for embodiment in benches or seats known to the trade as piano benches, and I have illustrated my improvements in 15 the accompanying drawing in a structure of that type. Certain features are, however, desirable for use in other relations.

The main objects of this invention are:

First, to provide an improved knockdown 20 bench or seat which may be readily assembled and one which when assembled is very strong and rigid.

Second, to provide an improved knockdown bench or seat which when in the 25 knockdown may be very compactly arranged for shipment or storage.

Third, to provide an improved knockdown bench or seat in which the parts are economical to produce and may be quickly 30 assembled by an unskilled person or workman or by the user, without the aid of tools other than a screw driver.

Further objects, and objects relating to 35 structural details, will definitely appear from the detailed description to follow.

I accomplish the objects of my invention by the devices and means described in the following specification. The invention is clearly defined and pointed out in the claims.

40 A structure which is a preferred embodiment of my invention is clearly illustrated in the accompanying drawing, forming a part of this specification, in which:

Figure I is a perspective view of a structure embodying the features of my invention.

Fig. II is a detail plan view with the top omitted.

Fig. III is a detail vertical section on a 50 line corresponding to line 3—3 of Fig. II, showing details of the leg securing means and other structural features.

Fig. IV is a detail section on a line corresponding to line 4—4 of Fig. I, showing 55 means for detachably securing the cross bar to the legs.

Fig. V is a horizontal section on a line corresponding to line 5—5 of Fig. I, showing details of the leg structure.

Fig. VI is a detail inverted view, showing 60 the details of the detachable connection for the longitudinal rail to the cross bar.

Fig. VII is a detail section on a line corresponding to line 7—7 of Figs. I and VI.

Fig. VIII is a detail vertical section on a 65 line corresponding to line 8—8 of Fig. I, showing the top open.

Fig. IX is a detail perspective view showing a leg provided with a capital.

Fig. X is a detail vertical section on a 70 line corresponding to line 10—10 of Fig. IX.

Referring to the drawing, I provide a rigid, permanently assembled, rectangular frame or bed, designated generally by the numeral 1, and formed of side pieces 2 and 75 end pieces 3 having, in the structure illustrated, mitered joints. The inner sides of the frame pieces, in the embodiment illustrated, are grooved at 4 to receive the edges of the bottom 5. Fillet blocks 6 are arranged in the corners, the fillet blocks being permanently secured in position by glue or otherwise so that they constitute reinforcing members for the frame. Below the bottom 80 the corner blocks 7 are permanently secured 85 in position. The lower faces of these corner blocks 7 are flush with the lower edges of the frame members 2 and 3.

The upper ends of the legs 8 abut the 90 lower edges of the frame members and corner blocks 7. The legs have longitudinal bores 9 therein in which are seated nuts 10.

The nuts 10 are securely retained in the legs by filler blocks 11 superimposed thereon and glued in the bores. These filler blocks 95 preferably have spiral grooves 12 which permit their being inserted more easily and the grooves also permit the glue to work or spread more thoroughly as the blocks are inserted.

100 The corner blocks 6 and 7, the bottom 5, and these filler blocks have aligned holes for the attaching bolts 13. The bolts 13 clamp the legs securely to the frame and provide a strong rigid connection. The corner fillers 7 are preferably countersunk at 14 to receive the heads of the bolts.

105 The legs are connected in pairs by cross bars 15. These cross bars are arranged with their ends abutting the inner sides of the 110 legs and have longitudinal bores 16 therein in which the nuts 17 are seated and retained.

by superimposed filler blocks 18 the same as the nuts are retained in the legs described.

The bolts 19 are arranged through the legs from the outer sides thereof. The 5 longitudinal rail 20 is provided with dovetail tenons 21 at its ends, while the cross bars have corresponding dovetail mortises 22 opening from the lower edges thereof. The rail 20 is provided with angle coupling 10 plates 23 secured to the under side of the rail 20 by screws 24 and to the under side of the cross bars by screws 25 which are disposed at each side of the mortises (see Fig. VI).

15 When a bottom 5 is present the top 26 is preferably hinged to the frame at 27 so that it may be opened to permit articles, such as sheet music, to be placed in the compartment within the frame. A slotted link 20 28 supports the cover in its open position. When the structure is disassembled the legs, the leg cross bars, and the longitudinal rail may be arranged within the compartment for transportation or storage.

25 The parts of the structure are simple and economical to produce and the structure is of advantage even when it is to be assembled in the factory. However, it is particularly desirable for use in shipping in the 30 knockdown and this is of special advantage at the present time when it is desirable to relieve as much as possible the burden on transportation, and is in compliance with requirement or requests of the railroad administration to this end.

A further advantage of this construction is that the ornamentation for the legs may be made as desired. If beading or other scroll work is desired, it may be added to 40 the frame, thus enabling the manufacture of the plain frames which may be conveniently stored in large quantities and the ornamentation thereof made according to order, thus resulting in a very great saving 45 of lumber as well as labor.

In the modification shown in Figs. IX and X the legs are provided with horizontal capitals 29 which are in the form of caps fitting over the upper ends of the legs so 50 that they are clamped in position, thereby constituting, in effect, a part of the leg.

I have illustrated and described my improvements in one form in which I have embodied the same for the market. I have 55 not attempted to illustrate or describe other modifications or adaptations which I contemplate, as I believe the disclosure made will enable those skilled in the art to which my invention relates to embody or adapt 60 the same as may be desired.

Having thus described my invention, what I claim as new and desire to secure by Letters Patent, is:

1. In a knockdown bench, the combination 65 of a rectangular frame comprising side

and end members disposed on edge, said side and end members being grooved on their inner sides to receive a bottom, a bottom board arranged with its edges in said grooves, corner fillet blocks secured in the 70 corners of said frame above said bottom board with their lower ends thereon, corner blocks disposed in the corners of said frame below said bottom, pairs of legs disposed with their upper ends abutting the lower 75 edges of the frame members and the lower corner blocks, said legs having nuts seated in longitudinal bores in their ends and retained therein by superimposed filler blocks glued in the bores, said corner blocks, bottom, 80 and filler blocks having aligned vertical bores therein, bolts arranged through said bores to engage said nuts whereby the legs are supported and clamped to the frame, cross bars for said pairs of legs disposed with their ends abutting the inner 85 sides of the legs and having nuts seated in longitudinal bores in their ends and retained therein by superimposed filler blocks glued in the bores, bolts arranged through the 90 legs and said filler blocks to engage said nuts whereby the cross bars are detachably secured to the legs, a longitudinal rail provided with dove-tailed tenons at its ends, said crossbars having dove-tailed mortises 95 for said tenons open at the bottom of the cross bars, coupling plates at the ends of said rail projecting under said cross bars and secured thereto by screws disposed at each side of said mortises therein, and a 100 top hinged to said frame whereby when the legs, rail, and cross bars are disassembled they may be packed within the frame.

2. In a knockdown bench, the combination 105 of a rectangular frame comprising side and end members disposed on edge, corner fillet blocks secured in the corners of said frame, pairs of legs disposed with their upper ends abutting the lower edges of the frame, said legs having nuts seated in longitudinal bores in their ends and retained 110 therein by superimposed filler blocks glued in the bores, said corner blocks, bottom, and filler blocks having aligned vertical bores therein, bolts arranged through said bores 115 to engage said nuts whereby the legs are supported and clamped to the frame, cross bars for said pairs of legs disposed with their ends abutting the inner sides of the legs and having nuts seated in longitudinal 120 bores in their ends and retained therein by superimposed filler blocks glued in the bores, bolts arranged through the legs and said filler blocks to engage said nuts whereby the crossbars are detachably secured to the 125 legs, a longitudinal rail provided with dove-tailed tenons at its ends, said crossbars having dove-tailed mortises for said tenons open at the bottom of the cross bars, coupling plates at the ends of said rail pro- 130

jecting under said cross bars and secured thereto by screws disposed at each side of said mortises therein, and a top on said frame.

- 5 3. In a knockdown bench, the combination of a rectangular frame comprising side and end members disposed on edge, said side and end members being grooved on their inner sides to receive a bottom, a bottom board arranged with its edges in said grooves; corner fillet blocks secured in the corners of said frame above said bottom with their lower ends thereon, corner blocks disposed in the corners of said frame below said bottom, pairs of legs disposed with their upper ends abutting the lower edges of the frame members and the lower corner blocks, said legs having nuts seated in longitudinal bores in their ends and retained therein by superimposed filler blocks glued in the bores, said corner blocks, bottom, and filler blocks having alined vertical bores therein, bolts arranged through said bores to engage said nuts whereby the legs are supported and clamped to the frame, and a top hinged to said frame whereby when the legs, rail, and cross bars are disassembled they may be packed within the frame.
- 30 4. In a knockdown bench, the combination of a rectangular frame comprising side and end members disposed on edge, corner fillet blocks secured in the corners of said frame, pairs of legs disposed with their upper ends abutting the lower edges of the frame, said legs having nuts seated in longitudinal bores in their ends and retained therein by superimposed filler blocks glued in the bores, said corner blocks, bottom, and filler blocks having alined vertical bores therein, bolts arranged through said bores to engage said nuts whereby the legs are supported and clamped to the frame, and a top on said frame.
- 45 5. In a knockdown bench, the combination of a frame, legs disposed with their upper ends abutting the frame, said legs having nuts seated in longitudinal bores in their upper ends and retained therein by superimposed filler blocks glued in the bores, bolts arranged through the frame to engage said nuts whereby the legs are supported and clamped to the frame, cross bars for said legs disposed with their ends abutting the inner sides of the legs and having nuts seated in longitudinal bores in their ends and retained by superimposed filler blocks glued in the bores, bolts arranged in said legs and filler blocks to engage said nuts whereby the cross bars are detachably secured to the legs, a longitudinal rail detachably secured to said cross bars, and a top on said frame covering the said leg attaching bolts.
- 60 whereby the cross bars are detachably secured to the legs, a longitudinal rail provided with dovetailed tenons at its ends, said cross bars having dovetailed mortises for said tenons open at the bottom of the cross bars, coupling plates at the ends of said rail projecting under said cross bars and secured thereto by screws disposed at each side of the mortises therein, and a top on said frame covering the said leg attaching screws.
- 65 6. In a knockdown bench, the combination of a frame, legs disposed with their upper ends abutting the frame, said legs having nuts seated in longitudinal bores in their upper ends and retained by superimposed filler blocks glued in the bores, bolts arranged in said legs and filler blocks to engage said nuts whereby the cross bars are detachably secured to the legs, a longitudinal rail provided with dovetailed tenons at its ends, said cross bars having dovetailed mortises for said tenons open at the bottom of the cross bars, coupling plates at the ends of said rail projecting under said cross bars and secured thereto by screws disposed at each side of the mortises therein, and a top on said frame covering the said leg attaching bolts.

70 said rail projecting under said cross bars and secured thereto by screws disposed at each side of the mortises therein, and a top on said frame covering the said leg attaching bolts.

75 6. In a knockdown bench, the combination of a frame, legs disposed with their upper ends abutting the frame, said legs having nuts seated in longitudinal bores in their upper ends and retained therein by superimposed filler blocks glued in the bores, bolts arranged through the frame to engage said nuts whereby the legs are supported and clamped to the frame, cross bars for said legs disposed with their ends abutting the inner sides of the legs and having nuts seated in longitudinal bores in their ends and retained by superimposed filler blocks glued in the bores, bolts arranged in said legs and filler blocks to engage said nuts whereby the cross bars are detachably secured to the legs, a longitudinal rail detachably secured to said cross bars, and a top on said frame covering the said leg attaching bolts.

80 7. In a knockdown bench, the combination of a frame, legs disposed with their upper ends abutting the frame, said legs having nuts seated in their upper ends, bolts arranged through the frame to engage said nuts whereby the legs are supported and clamped to the frame, cross bars for said legs, a longitudinal rail provided with dovetailed tenons at its ends, said cross bars having dovetailed mortises for said tenons open at the bottom of the cross bars, coupling plates at the ends of said rail projecting under said cross bars and secured thereto by screws disposed at each side of the mortises therein, and a top on said frame covering the said leg attaching screws.

85 8. In a knockdown stool or bench, the combination of a rectangular frame comprising side and end members disposed on edge, said side and end members being grooved on their inner sides to receive a bottom, a bottom board arranged with its edges in said grooves, corner fillet blocks secured in the corners of said frame above said bottom board with their lower ends thereon, corner blocks disposed in the corners of said frame below said bottom, pairs of legs disposed with their upper ends abutting the lower edges of the frame members and the lower corner blocks, said legs having nuts seated in their upper ends, said corner blocks and bottom having alined vertical bores therein, and a top on said frame covering the said leg attaching bolts.

90 9. In a knockdown stool or bench, the combination of a rectangular frame comprising side and end members disposed on edge, corner fillet blocks secured in the corners of said frame, legs disposed with their upper ends abutting the lower edges of the frame, said legs having nuts seated in their upper ends.

ends, said corner blocks having vertical bores therein, and a top on said frame covering said leg attaching bolts.

10. In a knockdown stool or frame, the combination of a rectangular frame comprising side and end members disposed on edge, corner fillet blocks secured in the corners of said frame, legs disposed with their upper ends abutting the lower edges of the frame, said legs having nuts seated in their upper ends, said corner blocks having vertical bores therein, bolts arranged through said bores to engage said nuts whereby the

legs are supported and clamped to the frame, crossbars for said pairs of legs detachably secured thereto, a longitudinal rail detachably secured to said cross bars, and a top on said frame covering said leg attaching bolts. 15

In witness whereof, I have hereunto set my hand and seal in the presence of two 20 witnesses.
